(57) **CLAIM**

The ornamental design for a dental airpolisher gun, as shown and described.

DESCRIPTION

FIG. 1 is a perspective view of a first embodiment of a dental airpolisher gun;

FIG. 2 is a lower perspective view thereof;

FIG. 3 is another lower perspective view thereof;

FIG. 4 is a side elevation view thereof;

FIG. 5 is another side elevation view thereof;

FIG. 6 is a front elevation view thereof;

FIG. 7 is a back elevation view thereof;

FIG. 8 is a top plan view thereof;

FIG. 9 is a bottom plan view thereof;

FIG. 10 is a perspective view of a second embodiment of a dental airpolisher gun;

FIG. 11 is a lower perspective view of the dental airpolisher gun shown in FIG. 10;

FIG. 12 is another lower perspective view of the dental airpolisher gun shown in FIG. 10;

FIG. 13 is a side elevation view of the dental airpolisher gun shown in FIG. 10;

FIG. 14 is another side elevation view of the dental airpolisher gun shown in FIG. 10;

FIG. 15 is a front elevation view of the dental airpolisher gun shown in FIG. 10;

FIG. 16 is a back elevation view of the dental airpolisher gun shown in FIG. 10;

FIG. 17 is a top plan view of the dental airpolisher gun shown in FIG. 10; and,

FIG. 18 is a bottom plan view of the dental airpolisher gun shown in FIG. 10.

The claimed design is a dental airpolisher gun, which is a dental spray gun design to polish teeth. The dental airpolisher guns shown in FIGS. 1-9 and FIGS. 10-18, for example, generally include a nozzle, spray gun, and powder tank. In an example use, hydrogen peroxide in the powder tank may be propelled to the surface of the teeth through the nozzle. Then, the excess of the hydrogen peroxide may be drawn up with the spray gun.
